DON N. THOMPSON, OF SYRACUSE, NEW YORK, ASSIGNOR TO PASS & SEYMOUR INC.,
OF SOLVAY, NEW YORK, A CORPORATION OF NEW YORK.

LAMP SOCKET.

Application filed February 2, 1921. Serial No. 441,947.

This invention relates to electrical appliances as lamp sockets, and has for its object a particularly simple and efficient wire clamping terminal therefor; and a particularly simple and efficient arrangement of the wire terminals on the base of the socket. The invention consists in the novel features and in the combinations and constructions hereinafter set forth and claimed.

In describing this invention, reference is had to the accompanying drawings in which like characters designate corresponding parts in all the views.

15 Figure 1 is a vertical sectional view of a socket embodying my invention.

Figure 2 is an elevation, partly broken away, and parts being omitted.

Figure 3 is a rear end view, the cap being removed.

Figure 4 is a sectional view on the plane of line 4—4, Fig. 3, the cap omitted in Fig. 3 being shown in Fig. 4, and the lamp terminals being also omitted.

25 Figure 5 is a front end view of the socket.

This lamp socket comprises a base of insulation having a recess or socket in one end, lamp terminals mounted in the recess, wire terminals mounted on the rear end of the base, screws extending lengthwise of the base from the recess and threading into the wire terminals and mechanically and electrically connecting the wire terminals 35 with the lamp terminals, and a cap covering the rear end of the base.

1 designates the base of insulation, which is here shown as cylindrical in form and formed with a recess or socket 2 in its front end. 3 and 4 are respectively, the outer and central lamp terminals located in the recess 2. 5 and 6 respectively the wire terminals mounted on the rear face of the base or in recesses or depressions 7 in the rear 45 face of the base.

8 and 9 are respectively, screws extending through passages 10, 11 leading from the recess 2 and opening through the rear face of the base or the bottoms of the depressions 7, enlargements or countersinks 12, 13 being located at the upper ends of the passages 10 and 11. The screw 8 passes through an arc-shaped clamping member or washer 14 which seats on the bottom flange of the shell or outer lamp

terminal 3, and the screw 9 extends through the outer end of the central terminal 4. The heads of the screws bear on the washer 14 and the base of the central terminal 3 respectively. Each wire terminal 5, 6 has a portion extending into the countersink 12 or 13, and as here shown, each terminal is U-shaped in general form, and has laterally turned lips or flanges 15 at the ends of its arms which lap the outer rear face of the base or the bottom of the depression 7, and the screw 8 or 9 threads into the intermediate part of the U-shaped formation. Springs 5^a, 6^a press outwardly on the terminals 5, 6 respectively, these 60 springs encircling the screws 8, 9 and being interposed between the intermediate portions of the U-shaped terminals and internal shoulders 10^a, 11^a in the passages 10, 11. These springs tend to hold the screws 65 from endwise movement and to lift or unclamp the terminals during unscrewing of the screws.

16 is a cap on the rear end of the base and enclosing the wire terminals and the 70 contiguous ends of the service wires, this cap being held in position by fastening members, as screws extending lengthwise of the body and accessible through the socket or recess 2, and as here shown, the cap is held in position by screws 17 extending through passages 18 opening through the bottom of the socket or recess 2 and through the rear face of the body, the heads of the screws being located in the socket. The recess 2 and the outer terminal 3 are cut away to expose the heads of these screws whereby they are accessible from the front side of the socket.

90 In operation, the wire extends between one of the flanges 11 and the bottom of the recess 7 and is curved around so that the end of the wire lies under the other lip or flange 15. Thus by turning the screws 10, 11, all parts will firmly clamp in position.

95 What I claim is:—

1. In an electrical appliance, the combination of a base of insulation having a passage therethrough, a wire terminal having a portion extending lengthwise into the passage, a wire engaging part at its outer end overlying the surface of the base at the outer end of the passage and an angular extending portion at its inner end and a screw extending lengthwise of the passage and 100

105

110

threading into the angular portion at the inner end of the wire terminal.

2. In an electrical appliance, the combination of a base of insulation having a passage therethrough, a wire terminal having a U-shaped portion extending into the passage, the intermediate part of the U-shaped portion being located at the inner end of the wire terminal within the passage and the terminal having wire engaging parts at the outer ends of the arms of the U, said parts being located outside of such passage and a screw arranged in the passage and threading into the intermediate part of the U-shaped terminal.
3. In an electrical appliance, the combination of a base of insulation formed with a passage, a wire terminal U-shaped in general form and extending into the passage, the wire terminal having outturned lips at the ends of the arms of the U-shaped formation for engaging wires, said lips being opposed to the surface of the base around the passage and a screw extending through the passage and threading into the intermediate part of the U-shaped terminal of the passage, and a spring in the passage arranged to thrust the wire terminal out of the passage when disengaged from the screw, substantially as and for the purpose described.
4. In an electrical appliance, the combination of a base of insulation, formed with a passage, a wire terminal U-shaped in general form and extending into the passage,

the wire terminal having outturned lips at the ends of the arms of the U-shaped formation for engaging wires, said lips being opposed to the surface of the base around the passage and a screw extending through the passage and threading into the intermediate part of the U-shaped terminal of the passage, and a spring in the passage arranged to thrust the wire terminal out of the passage when disengaged from the screw, substantially as and for the purpose described.

5. In an electrical appliance, the combination of a base of insulation having a passage therethrough, a wire terminal having a U-shaped portion extending into said passage and having wire engaging parts outside of such passage and a screw arranged in the passage and threading into the intermediate part of the U-shaped portion, and a spring arranged in the passage and thrusting against the intermediate part of the U-shaped formation to thrust the wire terminal out of the passage when the same is disengaged from the screw, substantially as and for the purpose set forth.

In testimony whereof, I have hereunto signed my name, at Syracuse, in the county of Onondaga and State of New York, this 3rd day of January, 1921.

DON N. THOMPSON.
